DESIGN FOR A COMBINATION BABY WALKER AND STROLLER

Frank P. Fletcher, Pasadena, Calif., assignor to Fletcher Aviation Corp., Pasadena, Calif., a corporation of California

Application May 12, 1945, Serial No. 119,524

Term of patent 14 years

(Cl. D14—14)

To all whom it may concern:

Be it known that I, Frank P. Fletcher, a citizen of the United States, residing in Pasadena, in the county of Los Angeles and State of California, have invented a new, original, and ornamental Design for a Combination Baby Walker and Stroller, of which the following is a specification, reference being had to the accompanying drawing, forming part thereof.

In the drawing,

Fig. 1 is a perspective view of a combination baby walker and stroller illustrating my new design;

Fig. 2 is a plan view thereof;
Fig. 3 is a side elevational view thereof;
Fig. 4 is a front elevational view thereof; and
Fig. 5 is a rear elevational view thereof, a portion of the handle being broken away for convenience of illustration.

I claim:

The ornamental design for a combination baby walker and stroller, as shown.

FRANK P. FLETCHER.
